UNITED STATES PATENT OFFICE.

LELAND S. MAEDE, OF OAKLAND, CALIFORNIA.

APPARATUS FOR SEALING CANS IN VACUUM.

1,119,361.

Specification of Letters Patent.

Patented Dec. 1, 1914.

Application filed October 6, 1913. Serial No. 793,642.

To all whom it may concern:

Be it known that I, LELAND S. MAEDE, a citizen of the United States, residing at Oakland, in the county of Alameda and 5 State of California, have invented new and useful Improvements in Apparatus for Sealing Cans in Vacuum, of which the following is a specification.

This invention relates to apparatus for 10 packaging coffee and other substances in vacuum.

It is the object of this invention to provide apparatus for effecting a substantially complete removal of air from cans and their 15 contents and thoroughly sealing the cans thereafter.

Another object is to provide means in a 20 double-seaming machine for exhausting air from cans immediately prior to the sealing operation which will permit of either a constant or irregular feed of cans to the machine, in which each can will be subjected to the exhausting action before sealing a sufficient length of time to effect a practically 25 complete removal of air from the cells of the granular material contained therein, and in which the can will not be exposed to atmosphere in the interval of time between the exhausting and sealing operations.

30 A further object is to provide an apparatus of the above character in which the exhausting and sealing operations are accomplished in a vacuum chamber and in which air is being removed from one can while 35 a preceding can is being capped, thus eliminating transposing a can from one machine to another and thereby attaining a rapid handling of the cans and consequent large capacity at a minimum of expense, and by 40 which a uniform exhaustion of the cans is obtained.

The present invention is particularly designed for use in packaging ground coffee, although it is applicable in packing other 45 substances.

It is a well known fact that when roasted and ground coffee is exposed to the air, a chemical action takes place, which results in a deterioration of the coffee flavor or 50 aroma, this chemical action being very rapid when the coffee grain is broken. It is, therefore, necessary, in order to keep roasted and ground coffee from deteriorating, to withdraw the air from the can after pack-

ing, and seal it, all of which is accomplished 55 by the hereinafter-described apparatus.

The invention primarily resides in the combination of a vacuum chamber, with a double-seaming device inclosed in the vacuum chamber, means for maintaining a constant 60 vacuum in the chamber, means for delivering and discharging the cans to and from the sealing mechanism through the walls of the vacuum chamber, and means to hold the conveying device stationary while 65 the cans are being sealed.

The invention further consists of the parts and the construction and combination of parts as hereinafter more fully described and claimed, having reference to the accompanying 70 drawings, in which,—

Figure 1 is a plan view of the invention. Fig. 2 is a side elevation of same. Fig. 3 is a detail section and plan view on the line *a—a* of Fig. 2. Fig. 4 is a rear elevation, 75 with parts broken away. Fig. 5 is an enlarged detail section in elevation on the line *b—b* of Fig. 4. Fig. 6 is a vertical section and elevation on the line *c—c* of Fig. 1, with parts broken away. Fig. 7 is a horizontal 80 section and plan view on the line *d—d* of Fig. 6. Fig. 8 is a vertical section and elevation on the line *e—e* of Fig. 1. Fig. 9 is a diagram of the complete apparatus. Fig. 10 is a detail vertical section of a can adapted 85 to be operated on by the can sealing mechanism employed in this invention. Fig. 11 is a detail in perspective showing the turret-casing construction.

In the drawings A represents the base 90 plate of a can heading machine of any suitable description, the machine here shown being of the double-seamer type, including a rotary seamer-head 2, mounted on a vertical shaft 3, journaled in suitable bearings in a 95 housing A', carried by the base plate A. The shaft 3 is rotated from a drive shaft 4, through beveled gears 5 and 6; the drive shaft 4 being rotated through a pulley wheel 7 from any suitable source of power. 100 A worm gear 8 on the drive shaft 4 meshes with a corresponding worm gear 9 on a vertical shaft 10, which leads downward through the base plate A and has an arm 11 and segment 12 on its lower end adapted to 105 rotate a Geneva wheel 13, mounted on a shaft 14, journaled in suitable bearings in the base plate A. The lower end of the

- shaft 10 is provided with a groove cam 16, adapted to actuate a lever 17, connecting with a plunger 18, guided in the base plate A beneath the seamer-head 2. A cam 19 on 5 the shaft 10 is arranged to operate a lever 20, connected at its outer end with a sleeve 21, carrying cams 22 by which the seamer disks are advanced or retracted in relation to each other. The parts just described are 10 included in a well-known type of double-seaming machine.

In carrying out the present invention, the double-seaming mechanism is inclosed within an air-tight housing of peculiar construction. This housing consists of a lower base portion 23 on which the base plate A is carried; the base 23 forming an inclosure for the underside of the base plate A and the operating parts therebeneath. The rear 20 wall of the base 23 of the housing extends upward to a point slightly above the seamer-head 2, which raised portion extends forwardly along the sides a suitable distance. A flange 24 is formed on the upper 25 edge of the base 23 and extends entirely around same.

Secured to the lower portion of the base 23 and covering the forward portion of the base plate A is a plate 26, having an 30 upwardly projecting wall 27 on one of its ends adapted to abut against the vertical edges of the raised portion of the base 23; the plate 26 with its wall member 27 being secured in place by means of bolts 28, or 35 other suitable fastenings. The upper edge of the wall 27 is formed with a horizontal flange 27', the upper face of which is on a level with the upper face of the flange 24 on the raised portion of the base 23.

40 Formed in the wall 27 is an opening 29, through which a portion of the periphery of a star wheel or turret 30, mounted on the shaft 14, extends. The star wheel 30 is formed with a series of recesses 31 in its periphery, in this case six in number, which are approximately of a diameter corresponding to that of the can to be sealed. The central portion of the star wheel 30 is inclosed in a casing 32 which has a close 45 50 55 60 65 70 75 80 85 90 95 100 105 110 115 120 125 130 135 140 145 150 155 160 165 170 175 180 185 190 195 operation of the arm 11 and segment 12 in the usual manner. The Geneva wheel 13 in rotating carries the star wheel 30 therewith, thus causing the can B in the recess 31 to pass from the exterior of the housing through the casing 32 into the interior of the housing, where it is brought to rest above the plunger 18. The plunger 18 is then caused to rise by means of the lever 17 and cam 16, so as to dispose the flange or rim of the can in engagement with the seamer 2, which then operates to double-seam the can in the usual manner. The plunger 18 on moving downward again restores the can in its supported position on the star wheel 30 by which it is advanced and finally ejected from the housing to a suitable conveyer not shown. In passing from the exterior of the housing to its interior, the can is inclosed in a recess 31 and carries into the housing such air as may be contained in the can and in the cells of a coffee-grain. In order to effect a complete removal of this air from the can, it is found necessary to cause the can to pause within the housing a short time before it is subjected to the sealing action. The star wheel 30 is therefore formed with such number and arrangement of can-receiving recesses 31 that when one of the recesses registers with the plunger 18, the succeeding recess carrying a can will be subjected to the action of the vacuum in the housing during the time the plunger 18 traverses its stroke and during the operation of the seamer. By this construction a practically absolute removal of air from the can is accomplished.

It will now be seen that by maintaining a vacuum within the housing a can and its contents will not be exposed to atmosphere after having the air removed therefrom, and before the sealing of the can is effected. This permits of a gasket usually employed between the can top D and the flange C being dispensed with, as a perfectly tight joint can be insured by coating either the margin of the cover D or the upper face of the flange C with a thin coat of gum or similar sealing material.

As a means for maintaining a close fit between the star wheel 30 and its casing 32, the latter is made in separable adjustable pieces, comprising a bottom piece f, a top piece g and side or end pieces h and i, as particularly shown in Fig. 11. The piece f contacts with the underside of the star wheel, the piece g contacts with the upper face and the pieces h and i abut against the vertical walls or periphery thereof; the end pieces h and i being formed with convex inner faces conforming to the curvature of the periphery of the star wheel. The end pieces are formed with vertical slots or perforations j, through which bolts k passing through the top and bottom plates

g and f extend; the bolts k serving to clamp the pieces of the casing together. Adjustment of the end plates to take up wear is effected by loosening the bolts k and moving the end plates against the turret and retightening the bolts; the slots j permitting of the necessary movement of the end plates.

The flanges to which the bolts 33 are secured are formed on the top and bottom plates g and f, and are indicated at l.

For the purpose of preventing the flow of air through the casing 32, the latter is made of a width greater than that of the can-receiving recesses 31, so that the said recesses will be completely closed when they pass from one side of the casing to the other on the rotation of the star wheel, and so that the can ingress and egress opening remains permanently closed irrespective of the position of the star wheel. The star wheel 30 and its casing thus form a valve through which the cans can be delivered to and from the interior of the vacuum housing without breaking the vacuum therein.

Having thus described my invention what I claim and desire to secure by Letters Patent, is:

1. A continuously-operating apparatus for sealing cans in vacuum comprising, in combination, a sealed casing having an opening therein; means for constantly maintaining a vacuum in said casing; a pocketed carrier mounted within said casing and having a portion projecting outwardly through said opening to receive the cans to be sealed from the exterior of the casing and to permit the removal of the sealed cans; means for imparting a step-by-step movement to said carrier; and a can-seaming device arranged within said casing and operable upon the successive cans while in place in the pockets in said carrier.
2. A continuously-operating apparatus for sealing cans in vacuum comprising, in combination, a sealed casing having an opening therein; means for constantly maintaining a vacuum in said casing; a wheel mounted horizontally within said casing and having a portion projecting outward through said opening, said wheel being provided with peripheral pockets to receive the cans to be sealed from the exterior of the casing and to permit the removal of the sealed cans; means for imparting a step-by-step rotary movement to said wheel; and a can-seaming device arranged within said casing and operable upon the successive cans while in place in said pockets.
3. A continuously-operating apparatus for sealing cans in vacuum comprising, in combination, a casing having an opening therein; means for constantly maintaining a vacuum in said casing; a pocketed carrier mounted within said casing and having a portion projecting outward through said

- opening to receive the cans to be sealed from the exterior of the casing and to permit the removal of the sealed cans; means coöperating with the walls of said casing and said carrier adjacent said opening to hermetically seal the casing; means for imparting a step-by-step movement to said carrier; and a can-seaming device arranged within said casing and operable upon the successive cans while in place in the pockets in said carrier.
4. A continuously-operating apparatus for sealing cans in vacuum comprising, in combination, a casing comprising a base having a vertical wall provided with an opening, and a dome removably mounted upon said wall; means for constantly maintaining a vacuum within said casing; a horizontally arranged pocketed carrier mounted within said base and having a portion thereof projecting outward through said opening to receive from the exterior of the casing the cans to be sealed and to permit the removal of the sealed cans; means for imparting a step-by-step movement to said carrier; means coöperating with said carrier and said vertical wall to hermetically seal said opening; and a can-seaming device arranged within said dome and operable upon the successive cans while in place in the pockets in said carrier.
5. In an apparatus of the character described, the combination with a vacuum chamber, of a rotary can conveying wheel extending through the walls of said chamber, a casing contacting the top, bottom and sides of the wheel, and means for adjusting said casing to compensate for wear thereof and maintain it in contact with the wheel.
6. In an apparatus of the character described, the combination with a vacuum chamber, of a rotary can conveying wheel, extending through the walls of said chamber, and a casing contacting the top, bottom and sides of the wheel, comprising a top and a bottom plate, and end plates adjustable in relation to the periphery of the wheel.
- In testimony whereof I have hereunto set my hand in the presence of two subscribing witnesses.

LELAND S. MAEDE.
